(57) **CLAIM**

The ornamental design for a heating equipment, as shown and described.

DESCRIPTION

FIG. 1 is a front elevational view of a heating equipment showing my new design;

FIG. 2 is a rear elevational view thereof;

FIG. 3 is a bottom plan view thereof;

FIG. 4 is a right side view thereof;

FIG. 5 is a perspective view thereof;

FIG. 6 is another perspective view thereof showing the sliding cover being partly slid inward; and,

FIG. 7 is another perspective view thereof showing the sliding cover being fully slid inward.

In the drawings, the broken lines depict environmental subject matter only and form no part of the claimed design.
